United States Patent Office.

HENRY BAILEY, OF NEW YORK, N. Y.

Letters Patent No. 62,920, dated March 19, 1867.

IMPROVEMENT IN STEAM ENGINES.

The Schedule referred to in these Letters Patent and making part of the same.

TO ALL WHOM IT MAY CONCERN:

Be it known that I, HENRY BAILEY, of the city, county, and State of New York, have invented a certain new and useful Improvement in Steam Engines and Pumps, of which the following is a full, clear, and exact description, reference being had to the accompanying drawing, forming part of this specification, and in which—

Figure 1 represents a partly sectional plan of a horizontal engine constructed according to my improvement; and—

Figure 2, a vertical longitudinal section of the same.

Like letters indicate like parts in both figures.

The nature of my invention consists in enclosing a revolving crank and its operating pitman, which connects with a piston working in a cylinder open at its one end, within a steam or water-tight box, preferably of a form corresponding to the travel described by the pitman, whereby a rotary motion may be obtained through a long connecting-rod, in a short space or compass, and a piston-rod is dispensed with; also, in combination with the foregoing, in pivoting the pitman to the piston within the body of the latter at or about the middle of its thickness, to the reduction of lateral pressure or twist upon the piston, and still further enhancing the compactness of the pump or engine for a given length of connecting-rod.

Referring to the accompanying drawing, which represents my invention as applied to a horizontal steam engine, A is the bed-plate of the engine; B its cylinder; C the valve-box or case; D the exhaust pipe; E the valve-rocking lever, worked by an eccentric, F, on the main shaft G, which is or may be provided with a suitably sized driving-pulley or pulleys. The cylinder B is open at its inner end and in uninterrupted communication with a steam-tight box, H, or, as it may be termed, chambered cylinder-head, within which the main shaft passing through a stuffing-box, I, projects, and carries inside of said box a crank or face plate, J, provided with an eccentric-pin to which the pitman K is attached at its outer end, while its inner end is pivoted to the piston L, within the body of the latter, and centrally or thereabouts of its depth or thickness. By this construction and arrangement of parts a piston-rod is dispensed with, lateral pressure or twist on the piston by the direct connection of the pitman reduced, and a longer connecting-rod in a given space obtained, which contributes to the efficiency of the engine, while the compactness effected is an important consideration. The chambered-head or box H is preferably of a shape on the inside corresponding to the course of travel described by the pitman, which reduces the waste of steam in opening the inner end of the cylinder to the exhaust, as compared with a square or other shaped box. In applying the invention to a pump, then the main shaft, instead of being rotated by the piston, becomes the driver to reciprocate the latter for operation in concert with suitable valves and suction and discharge pipes connected with the cylinder. In the application of my invention to the steam engine, it may here be observed that the inequality of power which occurs in ordinary reciprocating piston engines during the two strokes, by reason of the piston-rod detracting from the area presented to steam pressure on the piston on its one side or face, is here avoided. When the crank is made up of a disk with eccentric-pin, as shown in the drawing, then it is important that space should be allowed for steam to pass in rear of it so as to counteract inside pressure.

What I claim as my invention, and desire to secure by Letters Patent, is—

1. The combination, with the cylinder and its piston, of the steam or water-tight box or chambered cylinder-head, pitman, and revolving crank, all arranged for operation within said head in open communication with the cylinder, substantially as specified.
2. The chambered cylinder-head H, constructed with its internal form corresponding to the course described by the pitman in its action, substantially as shown and described.

HENRY BAILEY.
